UNITED STATES PATENT OFFICE.

ALFRED MELVILLE JAMES, OF DUNEDIN, NEW ZEALAND.

SKYLIGHT.

Application filed January 5, 1924. Serial No. 684,651.

To all whom it may concern:

Be it known that ALFRED MELVILLE JAMES, a subject of the King of Great Britain, residing at Dunedin, in the Dominion of New Zealand, has invented certain new and useful Improvements in and Relating to Skylights, of which the following is a specification.

This invention relates to skylights such as are ordinarily used in conjunction with buildings and for other similar purposes and has for its object to provide a skylight of a simple yet strong and efficient construction and in which there are no small grooves or condensation channels which are so positioned that they become ineffective through being choked with dirt and the like. The invention is adapted to be made with or without ventilating means as may be desired.

The invention consists in the features and arrangements and combinations of parts hereinafter described and more particularly pointed out in the claims.

Referring to the accompanying drawings which illustrate the preferred embodiment of the invention Figure 1 is a general perspective view of the improved skylight shown partly in section to illustrate the construction, Figure 2 is an enlarged cross sectional elevation of one of the sides showing the details of construction, Figure 3 is an enlarged part outside elevation of one of the sides as shown in Figure 2, Figure 4 is an enlarged cross sectional view of a supporting bar showing the method of construction, Figure 5 shows a modification of the construction of the said supporting bar shown in Figure 4. It will be seen that the improved skylight preferably comprises four sides 1 of galvanized sheet metal or other similar material which may be made all in one piece. These sides 1 are bent at right angles at their lower ends to form the usual base flashing 2 which is secured to the roof or the like in any usual manner. The end edges 3 of the bent side 2 may if desired be lead edged.

The upper parts 4 of the sides 1 are bent inwardly and are doubled at 5 as is clearly shown in Figure 2 to form a condensation groove 6 which prevents any driving rain from getting inside and also stops any direct down draft. The portions 7 of the sides 1 are provided with ventilation holes 8 and are bent at their upper extremities to

form grooves 9 which are designed to receive an asbestos packing cord 10.

Stiffening bars 11 are secured where necessary to the sides 1 by rivets 12 or other suitable means and these stiffener bars 11 are provided with an outwardly projecting flange 18 which is then turned vertically upwards again at 13. To the portion 13 of this stiffening bar 11 and to the flashing 17 on two sides and at the back of the skylight is preferably secured a flat strip of metal 14 by means of countersunk rivets 15. The glass 16 rests upon the asbestos cord 10 and is held securely in position by the flashing 17 which is secured to the horizontal portion 18 of the stiffener 11 by bolts 19.

At the lower end of the skylight or elsewhere stiffeners or supports 35 are secured by rivets 12 to the side 1 which act as stiffeners to the upper portions 7 of the sides 1 and these also prevent the glass from slipping.

A glazing bar 20 of which more than one may be used where necessary may be provided. This bar is not necessary where the skylight is narrow. The bar 20 see Figure 4 is constructed with a bottom bent up to form two sides 21 which are bent outwards and doubled back, and riveted as at 27^a to form condensation channels 22 the upper ends 23 being bent to form grooves 24 in which are placed asbestos cords 10 upon which the glass 16 rests. Ventilation holes 25 may be provided on each side. U shaped stiffening brackets 26 are provided at suitable intervals and are riveted with rivets 27 to the inner sides 23 of the centre bar 20. The panes of glass 16 are secured by means of flashing 29 which is secured to the stiffener brackets 26 by means of bolts 28. The bar 20 is secured by being sweated or otherwise to the sides 1 of the skylight so that the water in the condensation channels 22 passes into the main condensation channel 6 and hence to the roof by any suitable orifice such as for instance the ventilation holes 8.

In a modification of the central bar 20 as shown in Figure 5, no ventilation holes are provided and the sides 21 of the said bar 20 are deepened and are riveted to U shaped stiffening brackets 30. The condensation channel is constructed as shown in Figure 4 the upper extremities 31 of the sides 21 being bent to form a groove to receive the asbestos cord 10. The bolt 32 se-

curing the flashing 29 to the bracket 30 is bent at its lower end in a right angular direction and is provided with a shoulder 33, the end 34 passing through the sides 21 and 30 of the bar 20 and bracket 30 respectively and then secured by a rivet 35 or other suitable means.

I claim:

1. A skylight having sides with the lower ends thereof bent to form a flashing said sides being also so formed within the skylight as to provide condensation channels said sides further having their upper edges turned over to form a groove and seating 15 for an asbestos cord, stiffening bars secured to and adapted to strengthen said sides said stiffening bars being bent horizontally outwardly and then again bent vertically upwards, a sheet of glass adapted to rest on 20 said asbestos cord, a flashing adapted to

secure said sheet of glass firmly in position said flashing being secured to the horizontal portion of said stiffening bar substantially as described and for the purposes set forth.

25

2. In a skylight having sides whose lower ends are bent to form a flashing and being so formed within the skylight as to provide condensation channels, the combination with at least one substantially U-shaped glazing bar the sides of which are formed to provide condensation channels and the upper edges of which are bent to form grooves, of substantially U-shaped stiffening brackets secured to said bar, asbestos cord in said grooves, a cover for the skylight supported by the asbestos cord, and a flashing secured to the stiffening brackets and adapted to hold the cover firmly in position.

ALFRED MELVILLE JAMES.
